[57] CLAIM

The ornamental design for a combined toothbrush and container therefor, as shown and described.

DESCRIPTION

FIG. 1 is a perspective view of a combined toothbrush and container therefor embodying my new design;

FIG. 2 is a front side elevational view thereof;

FIG. 3 is a rear side elevational view thereof;

FIG. 4 is a top plan view thereof;

FIG. 5 is a bottom plan view thereof;

FIG. 6 is a left end elevational view thereof;

FIG. 7 is a right end elevational view thereof, and

FIG. 8 is a perspective view thereof, shown with the toothbrush enclosed in the container portion.
